UNITED STATES PATENT OFFICE.

LUCIUS T. GIBBS, OF HEMPSTEAD, NEW YORK; ANGELICA GIBBS, OF FLUSHING, NEW YORK, ADMINISTRATRIX OF SAID LUCIUS T. GIBBS, DECEASED, ASSIGNOR TO THE WESTINGHOUSE AIR BRAKE COMPANY, OF PITTSBURGH, PENNSYLVANIA, A CORPORATION OF PENNSYLVANIA.

CAR-HEATING SYSTEM.

1,026,349.

Specification of Letters Patent.

Patented May 14, 1912.

Application filed December 23, 1905. Serial No. 293,082.

To all whom it may concern:

Be it known that I, LUCIUS T. GIBBS, a citizen of the United States, residing at Hempstead, in the county of Nassau and State of New York, have invented certain new and useful Improvements in Car-Heating Systems, of which the following is a specification, reference being had to the drawing accompanying and forming part of 10 the same.

My invention relates to car-heating systems, and pertains more especially to cars propelled by internal combustion or explosive engines. With such motors it is customary to use a water-circulating system to cool the engine, and the chief object of my invention is to utilize such system for heating the car as well as for cooling the engine. This result is secured, broadly stated, 15 by carrying the water pipes through the car, the engine being located outside, preferably underneath, with the intention that the heat abstracted from the engine by water will be radiated into the interior of the car, thus 20 serving the double function of heating the car to an agreeable temperature and restoring the water to a sufficiently low temperature to cool the engine.

Another object of my invention is to provide means for keeping the engine and circulating system at a safe temperature in cold weather during such time as the car is standing idle, as for example in the yard. As is well understood it is not only necessary 30 to keep the water in the pipes from freezing, with consequent damage to the system or at least certain delay when the car is again wanted for use, but it is also desirable that the explosion engine itself be at a moderate 35 temperature when the car is to start. Otherwise, if the temperature of the engine be very low, as for example at the freezing point or below, the engine must first heat itself up before it can operate efficiently. 40 When the car is liable to be called into use 45 at any time it is also desirable that its interior be kept at a comfortable temperature, to avoid discomfort to the passengers. These results I secure by combining with the sys-

tem first described, an auxiliary heater of 50 any suitable kind, as for example a stove through which the water pipe or pipes pass. When the car is parked a fire may be started in the auxiliary heater. This will keep up a circulation around the engine, maintaining 55 both it and the interior of the car at any desired temperature. When the car is running this fire may be allowed to burn out, though it may of course be maintained as an auxiliary source of heat if for any reason, as 60 for instance unusually severe weather, the heat absorbed from the engine should not be sufficient to keep the car at the desired temperature.

It is also desirable that the temperature of 65 the car be readily controlled, and provision is therefore made for such control. This I may secure by regulating the flow of water through the car, but I prefer to secure the desired regulation by abstracting more or 70 less heat from the water, as may be necessary, before it enters the car.

For a more complete understanding of my invention reference may now be had to the annexed drawings, which show, somewhat 75 diagrammatically, the preferred arrangement.

Figure 1 is a side elevation of a passenger car body, part of the side wall being broken away to show the interior. Fig. 2 is a longitudinal section of the water-cooling apparatus, and Fig. 3 is an end view of the same.

The passenger car shown in Fig. 1 may be of any approved type or construction. The prime mover for furnishing the motive 85 power of the car is an explosive or internal combustion engine, shown diagrammatically at 1. The combustion of the hydrocarbon in such an engine liberates a considerable amount of heat, which must constantly be 90 withdrawn from the engine by a suitable cooling system. The cooling medium most commonly used is water, circulated in passages about the engine. It is this otherwise waste heat that I desire to utilize to warm 95 the interior of the car, and I propose to do so by leading through the car the pipes which convey the water to and from the

engine, so that the heat absorbed from the engine will be made to perform some useful function instead of being wasted by radiation outside the car. In the annexed drawing, 2 indicates the pipe conveying the heated water from the engine. This pipe is in communication with a radiating pipe or pipes, such as indicated at 3, extending through part or all of the car and serving as a heater or radiator for warming the car apartment, the water after giving up its heat being led back to the engine by a pipe 4.

It is desirable that means be provided for regulating the temperature of the interior of the car, and for this purpose I provide apparatus of suitable character for extracting more or less heat at will from the heated water before it enters the car. Convenient apparatus for such purpose is indicated at 5 in Fig. 1, and is shown more in detail in Fig. 2. It consists of a liquid-tight cooling drum 6, which may or may not be covered or incased with heat-insulating material, 7. Extending from end to end are longitudinal tubes 8, open at each end to the atmosphere. The interior of the drum is in communication with the pipe 2 in such manner, as shown in Fig. 2, that the water flowing from the engine to the car will pass through the drum. At the same time the motion of the car will cause a flow of cold air through the tubes 8, and as the latter are bathed in the hot water the heat of the same is rapidly absorbed, leaving the water relatively cool when it enters the radiating pipe 3. Pivoted at one side of the drum, so as to swing in a vertical plane transverse to the car, is a shield or screen 9, which may be raised and lowered by any convenient means, as a chain 10 extending through an opening 11 in the car floor 12. When it is desired that the car be heated to the maximum degree the screen is raised to cover all the tubes in the drum 6. To lower the temperature of the car the screen is lowered, so as to expose as many of the tubes as may be necessary and allow the cold air to pass through them. By adjusting the screen to the proper position the active radiating surface of the tubes 8 may be made as great or small as desired, and a corresponding amount of heat extracted from the water before it enters the car. In this way the temperature of the car can be easily and accurately regulated. The adjustable screen closure plate on the drum or cooler is also effective when the car is traveling in either direction to prevent the passage of air through the tubes. In this case the air pocketed in such tubes as are closed by the screen will usually be found to prevent the movement of the car from causing any considerable circulation of fresh air in those tubes, and the radiation therefrom will therefore be slight. If, however, the

regulation thus secured is not sufficient, both ends of the drum may be provided with screens, but as one would be a mere duplication of the other it does not seem necessary to illustrate the second.

As already explained, it is desirable that provision be made whereby the car may be heated when it is standing idle and the engine not running, and also to keep the engine in condition to start at a moment's notice. For such purpose the car may be provided with a heater 13 of any suitable type, having water-heating coils 14 in position to be heated by a fire in the fire pot 15. The heating coils are connected in the heating circuit, so that the water circulates through the former in its passage through the car. If the heat from the engine is not sufficient to keep the car at the desired temperature, as might be the case in very cold weather; or when the car is standing in the yards; a small fire may be kept in the heater 13, to bring the water to the proper temperature as it flows through the coils. This will not only keep the interior of the car comfortably heated, but also will maintain the engine in condition to be started at any time with at least a fair degree of efficiency.

In warm weather or at other times it may be desirable not to heat the car, and to take care of such circumstances I provide means whereby the cooling liquid can circulate entirely outside the car. This consists of a by-pass 16, connected to the pipe 4, and to the pipe 2 forward of the cooler 5. The pipe 2 has a valve 17, in front of the connection with the by-pass and the pipe 4 has a valve 18 in the rear of the connection, while the by-pass pipe itself is valved at 19 and 20 adjacent to the connections. When the water from the engine is to circulate through the car the valves 17 and 18 are opened and the by-pass valves 19, 20 closed; but when conditions make it desirable the valves 17 and 18 are closed and valves 19 and 20 opened, whereupon the water leaving the engine through pipe 2 will flow rearwardly through the by-pass to pipe 4 instead of through the radiating pipe 3, as will be readily understood. By partially opening all the valves 17, 18, 19, 20, part of the water will flow through the by-pass and part through the radiating pipe 3, so that any desired quantity of water may be sent through the former, with the emission of a proportionate amount of heat in the interior of the car. This method of regulating the heat of the car may be employed independently of the regulation afforded by the cooler 5, or in conjunction therewith, as desired.

It will be seen from the above description that my invention utilizes heat that would otherwise be wasted, and also provides for regulating and for supplementing such heat

at will, so as to take care of all contingencies that may arise. The system herein specifically shown is of course merely one embodiment of the invention, which may take a

5 variety of forms without departure from its proper scope as defined in the following claims.

What I claim is:

1. In a car heating system, the combination of an internal combustion engine and a water circuit to cool the same, said circuit including radiators or heaters located inside the car, and a cooler for the water located outside the car between the engine and said radiators or heaters, and means for varying at will the amount of radiating surface in the cooler which is exposed to the outside air.

2. In a car heating system, the combination of an internal combustion engine and a water circuit arranged to cool the same, said circuit including radiators or heaters located inside the car, and a cooler for the water, said cooler located outside the car between the engine and said radiators or heaters, and consisting of a hollow body having a duct extending therethrough for the passage of air, and means for controlling the flow of air through said duct.

3. In a car heating system, the combination of an internal combustion engine and a water circuit to cool the same, said circuit including radiators or heaters located inside the car, and a cooler for the water, said cooler located outside the car between the engine and said radiators or heaters and consisting of a hollow body having ducts extending therethrough for the passage of air, and means for controlling the flow of air through said ducts whereby the cooling surface may be varied.

4. In a car heating system, the combination of an internal combustion engine and a water circuit to cool the same, said circuit including radiators or heaters located inside the car, and a cooler for the water, said cooler located outside the car between the engine and said radiators or heaters and consisting of a hollow body having a plurality of ducts extending through the same from end to end and open to the atmosphere, and means for controlling the flow of air through said ducts whereby the cooling surface may be varied.

5. In a car heating system, the combination of an internal combustion engine and a water circuit to cool the same, said circuit including radiators or heaters located inside the car, and a cooler for the water, said cooler located outside the car between the engine and said radiators or heaters and consisting of a hollow body having a plurality of air pipes extending through the same from end to end and open to the at-

mosphere, and a shield or plate arranged to 65 cover an end of the cooler, said plate being movable to vary the number of tubes exposed to the atmosphere.

6. In a car heating system, the combination of an internal combustion engine and a water circuit to cool the same, said circuit including radiators or heaters located inside the car and a cooler for the water, said cooler located outside the car between the engine and said radiators or heaters and comprising 75 a hollow body having a plurality of air tubes extending through the same from end to end and open to the atmosphere, and a shield or plate pivotally mounted upon an end of the cooler and movable across the 80 ends of the tubes to vary the number of the latter exposed to the atmosphere.

7. In a car heating system, the combination of an internal combustion engine and a water circuit to cool the same, said circuit 85 including radiators or heaters, and a cooler for the water, said cooler located between the engine and said radiators or heaters, and means for varying at will the amount of effective radiating surface in the cooler. 90

8. In a car heating system, the combination of an internal combustion engine and a water circuit for cooling the same, said circuit including radiators or heaters located within the car body, and a cooler arranged 95 between the engine and said radiators or heaters, a by-pass around the engine and cooler, and means for diverting the flow of water from said radiators through the by-pass or from said by-pass through the radiators. 100

9. The combination of an internal combustion engine and a water circuit arranged to cool the same, said circuit including radiators or heaters for warming an apartment, 105 and a cooler for the water, and means for varying the effective cooling capacity of said cooler.

10. The combination of an internal combustion engine and a water circuit arranged 110 to cool the same, said circuit including radiators or heaters for warming an apartment, and a cooler for the water, said cooler having a radiating surface exposed to an air current, and means for varying the effective cooling capacity of said cooler by varying the said radiating surface thereof. 115

11. The combination of an internal combustion engine and a water circuit arranged 120 to cool the same, said circuit including radiators or heaters for warming an apartment, and a cooler for the water, said cooler having a radiating surface exposed to an air current, and an adjustable shield or screen for varying the effective cooling capacity 125 of said cooler by varying the said radiating surface thereof.

12. The combination of an internal com-

bustion engine, and a water circuit arranged to cool the same, said circuit including radiators or heaters for warming an apartment, and a cooler for the water, means for varying the effective cooling capacity of said cooler, a by-pass for cutting said radiators or heaters out of circuit, and means for caus-

ing the water to flow through said radiators or heaters or through said by-pass.
